UNITED STATES PATENT OFFICE.

CHARLES G. JOHANNESMEYER, OF GLENDALE, OHIO, ASSIGNOR TO THE LIBERTY MACHINE TOOL COMPANY, OF HAMILTON, OHIO, A CORPORATION OF OHIO.

METAL-PLANING MACHINE.

Application filed July 20, 1925. Serial No. 44,771.

My invention particularly relates to metal planing machine slide vertical movement mechanism.

Heretofore it has been customary to provide 5 rotatable screws, mounted in the heads, respectively, of a metal planing machine and to provide slide mechanism capable of operative engagement with the respective screws, whereby when the usual manually 10 operative control levers are actuated said mechanism is caused to operatively engage the respective rotatable screws and thereby impart vertical movement to the slides. Furthermore, it has been customary to provide 15 the manually operative control levers secured to the respective heads, whereby it usually is inconvenient for an operator to grasp the lever for positioning the slides, as when the heads are in an inaccessible position 20 on the cross rail whereby when the slide mechanism control levers are secured to the respective left and right or a plurality of heads it is necessary for an operator to shift his position from one head to another 25 when it is desired to impart vertical movement and properly position the respective tools relative to the work through actuation of the slide. The rotatable screws being rotatably mounted are relatively loosely connected, thereby affording considerably less 30 stability to the tool than when the screws are stationary. It is especially advantageous 35 to provide the tool with considerable stability whereby the finished product may be free from indentations and rugged surface, as well as materially reducing the cost 40 of manufacturing a highly efficient article for the reason that an operator of the machine is enabled to take heavy cuts, at high speed, from the work without the likelihood 45 of damaging the machinery or work caused by excessive vibration developed by "chattering" of the tool and without the likelihood of breaking the tool.

The objects of my invention are to provide simple, efficient, economical and practical means for elevating and lowering the slides of a metal planing machine; to provide means adapted to increase the stability 50 and reduce the vibration of the slides vertical movement and supporting mechanism

thereby considerably reducing the likelihood of "chattering" of the respective tools when a heavy cut is being taken from the work; to provide means adapted to eliminate and 55 simplify a considerable portion of the usual mechanism for elevating and lowering the slides of a metal planing machine; to provide means adapted to permit the elimination of loosely mounted and rotatable 60 screws, respectively, connected with the slides of a metal planer and to substitute therefor respective stationary screws; to provide means adapted to simplify the manual operative controls of said slides elevating and lowering means, whereby the operator of said controls may stand in one 65 position and control the slide vertical movement mechanism of a plurality of cross rail heads. 70

My invention consists in providing a stationary vertical screw connected with each slide of a metal planing machine; in providing mechanism capable of operative connection with the driving shaft and the respective screws and in positioning the slide movement controlling levers in close relation to each other, irrespective of the position of the respective heads. 75

My invention further consists in the construction, combination and arrangement of parts, as herein set forth and claimed. 80

In the drawings:

Fig. 1 is a front elevation of the cross rail and rail heads of a metal planing machine having my invention embodied therein and showing the head partly broken away, with parts in dotted lines and parts in section; 85

Fig. 2 is a section taken on a line corresponding to 2-2 in Fig. 1; and 90

Fig. 3 is a section taken on a line corresponding to 3-3 in Fig. 2.

In the preferred construction of my invention I provide stationary screws 1, respectively, secured to slides 2, respectively, of heads 3 suitably and slidably mounted on a usual cross rail 4 of a metal planing machine. Screws 1, respectively, have threaded upper ends 5 projecting through 95 webs 6, respectively, integral with the tops 100 of slides 2. Nuts 7, respectively, threaded

to the upper ends 5, respectively, of screws 1 are adapted to draw collars 8, respectively, integral with the screws, in close engagement with the lower sides, respectively, of webs 6, 5 whereby the screws are maintained in fixed position relative to the respective slides.

Nuts 9, respectively, threaded to screws 1, respectively, have nut gears 10 integral therewith. The nut gears 10, respectively, 10 are in permanent meshing engagement with gears 11 fixed to driven shafts 12, respectively, rotatably mounted in bearings 13, respectively, in saddles 14 slidably mounted on cross rail 4 as by recesses 15 and 16, respectively, in each saddle receiving longitudinal projection 17 and 18 integral with the cross rail. The saddles are maintained in slidable position on the cross rail by usual means and comprising longitudinal 15 plates 19, fixed to saddles 14, respectively, and in bearing engagement with shoulders 20 respectively of the cross rail 4.

Longitudinal shafts 21, respectively, have ends 22 and 23, respectively, mounted in 25 bearings 24 and 25, respectively, in ends 26 and 27 of cross rail 4. Hand levers 28, respectively, fixed to ends 23, respectively, of longitudinal shafts 21, are for the purpose of providing convenient means for 30 manually rocking or rotating the shafts for reasons hereinafter fully explained. Threaded tubes or members 29, respectively, splined to shafts 21, respectively, are received in holes 30, respectively, in blocks 31, respectively, integral with saddles 14. The tubes are maintained against longitudinal movement relative to the blocks as by integral collars 32 respectively, being drawn in close engagement with sides 33, respectively 35 of the blocks, by nuts 34, respectively, screwed in engagement with sides 35 of the blocks. Push nuts 36, respectively, threaded to ends 37, respectively, of tubes 29, have integral forks 38, respectively, received in 40 circumferential grooves 39, respectively in collars 40 slidably keyed to driving shaft 41 having its ends 42 and 43 respectively, journaled in ends 26 and 27 of cross rail 4.

It will be understood that the mechanism 50 hereinafter explained is similar in operations and construction for both the left and the right rail heads, whereby explanation of a single head will suffice for both.

Integral with collar 40 is tubular shank 55 44 slidably keyed to driving shaft 41 and journaled in block 31. Gear 45 fixed to end 46 of tubular shank 44 is adapted to be slid into and out of meshing engagement with gear 47 fixed to driving shaft 41, 60 whereby rotary movement of the driving shaft imparts rotary movement to nut 9 rotatably secured to the saddle against vertical movement as by integral nut gear 10 engaging the lower side of web 48 (integral 65 with the saddle) and by nut 49 threaded

to the upper external portion of nut 9 and screwed in engagement with the upper side of web 48.

Suitable means are provided for imparting rotary movement to driving shaft 41, 70 as by an electric motor (not shown) having operative connection with gear 50 fixed to projecting end 51 of the driving shaft.

Usual rotatable screws 52 and 53, respectively, are threaded to blocks 31, respectively, integral with the heads, whereby horizontal movement is imparted to the heads. 75

The mechanical operations of my invention are as follows:

Assume suitable means are provided for 80 imparting rotary movement to driving shaft 41 and that the mechanism is positioned, as shown in Fig. 1, wherein gear 45 is shown disengaged from driven shaft gear 47.

Hand lever 28 is manually operated for 85 partially rotating or rocking longitudinal shaft 21 whereby threaded tube 32 is caused to rotate sufficiently to impart longitudinal movement to push nut 36 through the quick lead threaded connection of the nut with end 37 of tube 32, whereby through engagement of integral fork 38 of push nut 37 with collar 40, driving shaft gear 45 is slid longitudinally on driving shaft 41 and into meshing engagement with gear 47 fixed 90 to driven shaft 12 journaled in saddle 14. Meshing engagement of driving shaft gear 45 with driven shaft gear 47 imparts rotary movement to driven shaft gear 11 which is in continuous mesh with nut gear 10 integral 95 with nut 9 threaded to stationary screw 1, whereby vertical movement is imparted to slide 2. The direction of the vertical movement imparted to the slide is dependent upon the directional rotation of driving shaft 41 which is controlled by the directional rotation of the original source of power communicated to the shaft, which in this case, as heretofore explained, is derived from a suitably positioned electric motor. 100

When slide 2 is properly positioned relative to head 3, lever 28 is manually operated and gear 45 is disengaged from meshing engagement with gear 47 thereby disconnecting the source of power from nut 9 threaded to stationary screw 1. 115

It is apparent that I have invented simple, efficient and practical means whereby the slide is adapted to be elevated and lowered relative to the head of a metal planing machine. The herein described mechanical connections of vertical stationary screws 1 are especially advantageous for the reason that a considerable portion of the mechanism of a usual metal planing machine is eliminated, as well as providing considerably more stability to the usual tool (not shown) fixed in a usual clapper box (not shown) secured to the slide. The substitution of stationary screws for the usual ro- 125

tatably mounted and loosely connected screws materially adds to the sturdiness of construction and durability of a metal planing machine, for the reason that the stationary screws are adapted to resist the upward thrust of the slide when a heavy cut is being taken from the work. Furthermore, the likelihood of "chattering" of the tool is reduced whereby the work may be finished 10 with comparatively few high speed and deep cutting operations and the work when finished has a smooth surface possessing a high gloss which adds materially to the appearance and value of the finished product.

15 Greater stability of the cutting tool which permits cuts to be taken from the work without the disadvantage of the usual "chatter" of the tool clearly reduces the cost of manufacturing the product.

20 My invention also is capable of being operated quickly and efficiently, as the operator is not compelled to control the vertical movement of the slide by manually operative means fixed to the respective heads 25 themselves, but he may remain in one position and control the vertical movement of the slides in both the left and right heads, whereas the usual metal planing machines are provided with slide vertical movement 30 controlling means secured to the respective heads, thereby compelling an operator to continuously change his position in accordance with the position of the heads on the cross rail when it is desired to elevate or 35 lower the slides. The inconvenient operations required in the usual type of mechanism for elevating and lowering the slides often result in inefficient and damaging operation of the metal planing machine as an 40 operator often will elevate or lower the cross rail itself for the purpose of properly positioning the tool relative to the work, solely because of the fact that the controlling lever for elevating and lowering the cross rail is 45 more convenient and accessible than the controlling levers for imparting vertical movement to the slides, and which sometimes effects serious damage to the metal planing machine, as well as lowering the efficient 50 operation of the machine for the reason that when the tool is extended a considerable distance below the head it is impractical and sometimes impossible to take a heavy cut from the work because of vibration or "chattering" of the tool which is developed, due 55 to a too great overhanging distance of the tool.

In reduction to practice I have found that the form of my invention illustrated in the drawings and referred to in the above description is the most efficient and practical and, therefore, it is my preferred embodiment. However, I realize that the conditions and the uses of my invention will vary 60 considerably and I desire to emphasize the

fact that while I have chosen to illustrate the form and construction of my invention by the herein drawings and explanations of the same, the form and explanations as relates thereto, is not intended to include all 70 the structures in which my invention may be incorporated. It is understood that my invention resides in the combination, arrangement and location of parts and in the details of construction, as hereinafter 75 claimed, and that changes in the precise embodiment of the invention can be made within the scope of what is claimed without departing from the spirit of the invention.

What I claim as new and desire to secure 80 by Letters Patent is:

1. In combination with a metal planing machine, a cross rail suitably mounted, a saddle slidably mounted on said cross rail, a slide slidably mounted on said saddle, a longitudinal shaft mounted on said cross rail, a manually operative lever fixed to said shaft, a stationary screw fixed to said slide, a nut gear threaded to said screw and rotatably mounted in said saddle and secured 90 against vertical movement therein, a threaded member fixed to said longitudinal shaft, a nut threaded to said threaded member, a driving shaft rotatably mounted in said cross rail, means for rotating said driving 95 shaft, a gear keyed to said driving shaft and adapted to operatively connect with said nut gear whereby operation of said manually operative lever is adapted to mesh said driving shaft gear with said nut gear for 100 elevating and lowering said slide relative to said saddle.

2. In combination with a metal planing machine, a cross rail slidably mounted, a head mounted on said cross rail and comprising a saddle and a slide slidably mounted thereon, a stationary screw fixed to said slide, a nut threaded to said screw, a nut gear integral with said nut, a longitudinal shaft rotatably mounted in said cross rail, a manually operative hand lever fixed to one 105 end of said shaft, a threaded member fixed to said shaft, a push nut threaded to said threaded member, a driving shaft mounted in said cross rail, means slidably mounted on said driving shaft and having operative connection with said push nut, a driving shaft gear keyed to said driving shaft and fixed to said means, a driven shaft mounted in said saddle, a driven gear fixed to each 110 end of said driven shaft and, respectively, capable of meshing with said driving shaft gear and in permanent mesh with said nut gear, whereby manual operation of said lever is adapted to mesh said driving shaft gear with one of said driven shaft gears for 115 elevating and lowering said slide on said saddle.

3. In combination with a metal planing 120 machine, a cross rail suitably mounted, a

head mounted on said cross rail, a stationary vertical screw fixed to the slide of said head, a nut threaded to said screw, a nut gear fixed to said nut, a driving shaft rotatably mounted in said cross rail, means slidably mounted on said driving shaft and adapted to form operative connection with said nut gear, a longitudinal shaft mounted in said cross rail, a manually operative hand lever

fixed to said longitudinal shaft and means 10 on said longitudinal shaft operatively connected with said slidably mounted means whereby operation of said lever is adapted to operatively connect said slidably mounted means with said nut gear for elevating and 15 lowering said slide.

CHARLES G. JOHANNESMEYER.
